UNITED STATES PATENT OFFICE.

WILHELM RIEHM, OF AUGSBURG, GERMANY, ASSIGNOR TO THE FIRM, MASCHINEN-FABRIK AUGSBURG-NUERNBURG, AKTIENGESELLSCHAFT, OF AUGSBURG, GERMANY, A GERMAN CORPORATION.

FUEL-IGNITION APPARATUS FOR INTERNAL-COMBUSTION ENGINES.

Application filed August 24, 1921. Serial No. 494,884.

(GRANTED UNDER THE PROVISIONS OF THE ACT OF MARCH 3, 1921, 41 STAT. L. 1313.)

To all whom it may concern:

Be it known that I, WILHELM RIEHM, a citizen of the German Republic, residing at Augsburg, Germany, have invented certain new and useful Improvements in Fuel-Ignition Apparatus for Internal-Combustion Engines (for which I have filed application in Germany, July 25, 1919), of which the following is a specification.

10 The present invention relates to apparatus for the solid injection of fuel into the cylinders of internal combustion engines, and relates particularly to Diesel or similar engines in which the air in the cylinders is 15 highly compressed before the fuel is injected.

In engines of this type it is common to employ a high pressure pump for injecting the fuel into the cylinder through an atomizing nozzle. In such a system, however, considerable difficulty has been experienced by after-flow or dripping of the fuel into the cylinder after the full injection pressure has been exerted by the pump. This dripping occurs due to the fact that the passage 25 between the injection valve and the pressure valve at the pump is filled with fuel which is not forced out during the stroke of the pump but which subsequently drips out due 30 partially to the reaction of the flexible walls of the oil passage and chiefly because of compressed air from the cylinder making its way up into this passage.

It has been proposed to place the pressure 35 valve of the pump very close to the injection valve so that the volume of the fluid passage between the two valves is small. Such an arrangement serves only to limit the quantity of fuel which will drip into 40 the cylinder, since all the liquid contained in the passage between the two valves will drain out as before. To avoid this it has been proposed to employ the injection valve of the cylinder simultaneously as a pressure 45 valve of the pump. Now at the starting of the engine the oil passage between the injection valve and the pressure valve is normally filled with air. This air is compressed at the pressure stroke of the pump piston 50 and expands again at the following suction stroke, thereby forcing back the delivered oil from the passage to the pump casing.

It is accordingly a principal object of the present invention to provide a fuel injection apparatus for internal combustion engines which avoids the above difficulties and at the same time does not interfere in any way with the normal operation of the engine, and which does not require special parts or otherwise add to the complication or cost of the engine. This is attained by providing besides the combined injection and pressure valve adjacent the cylinder of the engine, a pressure valve at the pump which is operative only during the starting 60 of the engine to prevent a back flow of the oil from the passage to the pump, and which may be rendered inoperative when the engine is running and the oil passage is totally 65 filled with oil.

I have illustrated a preferred embodiment 70 of my invention in the accompanying drawing, which is an elevational view, partly in section and largely diagrammatic, of an engine cylinder and its cooperating injection apparatus embodying my invention.

Referring to the drawing *a* indicates the 75 injection pump or similar device for forcing liquid fuel into the engine cylinder *g* through the connecting passage *f*. At the opening of the fuel passage *f* into the engine cylinder there is provided a combined pressure and injection valve *c*, here shown diagrammatically as a simple valve mounted upon a vertical stem and normally retained in closed position by means of a coil spring *h*. This valve, however, may be of any desired type adapted to inject fuel into the cylinder and to be closed at the end of the injection period.

At the starting of the pump the oil passage *f* is filled to a large extent with air. This air is compressed during the pressure stroke and then expands owing to its elasticity during the suction stroke of the pump, thereby disturbing the regular operation of the pump. To avoid this a pressure valve *d* is located at the pump and this valve is operative during the starting of the pump so as to prevent the return of fuel from the pump casing. When the engine is running under normal conditions, however, this pressure valve should be rendered inoperative. Any convenient means may be employed for

2

this purpose, but I have illustrated a plunger or a rod *e* having its end which is within the compression chamber of the pump *a* inclined upwardly at *k* and bearing against 5 the lower end of the valve stem *d*. Thus when the plunger *e* is moved to its innermost position, as shown, the valve *d* will be closed. An outward movement of the plunger which may be effected from the exterior 10 of the pump by grasping the outer end of the plunger, causes the base of the valve stem to ride up on the inclined portion *k* of the plunger and hold the valve *d* permanently in its open position so that it has no 15 effect upon the flow of the fluid. Valve *c* thus is the only valve which functions during the injection of fuel into the cylinder.

I have illustrated a preferred embodiment 20 of my invention, but it is to be understood that the form of the valves, the various means of control, and the like, may be varied within the full scope of the appended claims without departing from the spirit of 25 the invention.

25 I claim:

1. In a fuel injection apparatus for internal combustion engines, the combination with a fuel pump for injecting fuel into the engine cylinder at high pressure and a 30 passage connecting the pump with the cylinder, of a combined injection and pressure valve valve adjacent the engine cylinder for spraying the pumped oil into the cylinder and for preventing return flow of oil to the 35 passage, and a pressure valve located at the pump and adapted to be rendered operative only during the starting of the engine when the passage contains air, and when so operative serving to prevent the return of oil 40 from the passage into the pump.

2. In a fuel injection apparatus for internal combustion engines, the combination with a fuel pump for injecting fuel into the engine cylinder at high pressure, and a passage connecting the pump with the cylinder 45 of a combined injection and pressure valve adjacent the engine cylinder for spraying the pumped oil into the cylinder and for preventing return flow of oil to the passage and a manually operated valve located at 50 the pump and adapted to be rendered operative only during the starting of the engine, when the passage contains air, and when so operative serving to prevent the return of oil from the passage into the pump during 55 the suction stroke of the pump, the valve at all times permitting the flow of oil from the pump to the cylinder.

3. In a fuel injection apparatus for internal combustion engines, the combination 60 with a fuel pump for injecting fuel into the engine cylinder at high pressure and a passage connecting the pump with the cylinder of a combined injection and pressure valve adjacent the engine cylinder for spraying 65 the pumped oil into the cylinder and for preventing return flow of oil to the passage, and a valve located within the pump casting and controllable from the outside thereof, the said valve adapted to be rendered 70 operative only during the starting of the engine, when the passage contains air, and when so operative serving to prevent the return of oil from the passage into the pump during the suction stroke of the pump, the 75 valve at all times permitting the flow of oil from the pump to the cylinder.

In witness whereof I affix my signature.

Dr. WILHELM RIEHM.
